UNITED STATES PATENT OFFICE
CRANE

Harry F. Stofflet, Allentown, Pa.

Application August 7, 1942, Serial No. 453,936

7 Claims. (Cl. 212—27)

The objects of the invention are: to provide a crane having minimum overhead and end clearances so as to serve a maximum floor area with maximum hoisting height for a given height of building or supporting structure; to give a greater flexibility in handling loads; and to so simplify the construction and so locate and so simplify the power drive as to materially reduce the cost of construction, operation and maintenance.

These objects are accomplished by my invention, one preferred embodiment of which is shown in the accompanying drawing, in which—

Fig. 1 is a plan view of the crane.

Fig. 2 is a longitudinal section on the line 2—2 of Fig. 1.

Fig. 3 is a cross section, omitting the end truck, on the line 3—3 of Fig. 1.

Fig. 4 is a detail side view of one of the trolley sheaves and its braking mechanism.

Supporting opposite ends of the bridge beams *a*, *a* are the end trucks *b*, *b*, movable on the side rails *z*, *z*, of the supporting structure. Supported on one of the bridge beams, at each end thereof, is a frame *c* carrying a motor *d*. At each end of the bridge is a cable-winding drum *e*, the ends of which turn in bearings *g* carried by the beams *a*. Each motor *d* drives its corresponding drum *e* through reduction gearing *f* and *f'*.

The wheels *i* of the trolley frame *k* run on rails *h* on the beams *a*. Turnable on an axle carried by the trolley are two pairs of sheaves *m*, *n*, and *o*, *p*. Two wire ropes or cables *r* and *s* connect the drums *e* at opposite ends of the bridge, the ends of the ropes being wound upon the two drums. One rope *r* extends from one drum *e* successively around sheave *m*, a sheave *t'* on a sheave block *t* carrying the lifting hook *t* and sheave *n* to the other drum *e*. The other cable extends from one drum *e* successively around sheave *o*, another sheave *t'* on the sheave block *t* and sheave *p* to the other drum *e*. It will be understood that there may be any number of bights in the wire ropes *r* and *s* between the sheaves carried by the trolley and the sheaves on the lifting hook and therefore any corresponding number of sheaves on the trolley *k*; the four sheaves shown being adequate for a small crane or for light loads.

Carried by each sheave *m*, *n*, *o* and *p* is a brake drum *u* (see Fig. 4). Each brake drum carries a strap *v* one end of which is secured to a frame *w* and the other end of which is secured to a bell crank lever *x* pivoted on the frame *w* and operable by a solenoid *y*. The form of sheave brake shown is conventional and any suitable known

brakes for locking the sheaves against rotation may be substituted for brakes of the construction shown.

10 10 is the operator's cage and 11 the footwalks.

The electric connections to the motors *d* and solenoids *y* are not shown, as these are conventional.

The movements that it is desirable to impart to the load are the following: Lifting or lowering the load at full speed; lifting or lowering the load at half speed; moving the trolley along the bridge in either direction with no lifting or lowering of the load; moving the trolley along the bridge in either direction with simultaneous lifting or lowering of the load.

If it is desired to lift the load at full speed with no movement of the trolley, the brakes are not applied to any of the sheaves and both motors are actuated to turn the drums *e* in the direction required to wind the ropes thereon. The sheaves *m*, *n*, *o* and *p* being free to revolve, the shortening of the rope lengths between the drums will be wholly taken up by shortening the bights in the ropes between the trolley sheaves and the load, and the load will lift at high speed with no movement of the trolley.

By actuating only one motor to wind the rope on only one drum *e*, with no application of the brakes, the load will be lifted at half speed, the trolley remaining stationary.

If it is desired to move the trolley to the right, with no vertical movement of the load, the brakes are applied to all the sheaves *m*, *n*, *o* and *p* and the right-hand motor is actuated to wind the ropes on the right hand drum, the left-hand drum being meanwhile allowed to unwind. Similarly with all the brakes applied, by actuating the left-hand motor to wind up the ropes and the right-hand drum being allowed to unwind, the trolley will move to the left, with no vertical movement of the load.

If only sheaves *m* and *n* are braked and the drum at the right turned to wind the ropes thereon, the trolley will move to the right and at the same time the sheaves *o* and *p* will turn to lift the load. By braking only sheaves *o* and *p* and turning the drum at the left to wind the ropes thereon, the trolley will move to the left and at the same time the sheaves *m* and *n* will turn to lift the load.

50 A crane constructed substantially as described has a number of pronounced advantages.

The two single speed motors provide a two-speed lift, giving a greater range of hoisting speeds and a greater flexibility in handling loads.

55 Shift from half speed or less to full speed may be

instantly effected. This capacity is a very desirable feature, especially in serving machine tools, assembling parts, or loading and unloading machinery.

The height of the carriage or trolley *k* need be substantially no greater than the diameter of the trolley wheels *h*. The sheaves carried by the trolley may have their axes just high enough to clear the track. The trolley carries no motor. Therefore, the head room, that is, the height from rail to required clearance for moving parts, is reduced to a minimum, thereby obtaining a greater hoisting height. This close overhead clearance is of importance, since the required height of hoist can be obtained with a minimum height of building or crane supporting structure.

The construction shown and described, and particularly the location of the drums *e* at the extreme ends of the bridge beams, enable the load carrier to approach very close to the sides of the building or crane-supporting structure. These close end clearances enable the crane to serve a substantially maximum floor area.

The weight of the motors and drive being on the end trucks, excellent traction is secured.

The construction shown and described permits the elimination of the usual slide bars, current collectors, electrical equipment, wires and other elements required to provide current to the motors. This simplification, together with the elimination of the usual trolley drive, with no motor or motors on the trolley, enables the weight of the trolley to be materially reduced, and permits also the employment of lighter main supporting girders and bridge beams, well within the safety factor. These reductions in weight and simplifications of construction not only materially decrease construction cost, but decrease the amount of current required for both operation and maintenance.

What I claim and desire to protect by Letters Patent is:

1. In a crane, the combination with a supporting structure comprising end trucks and connecting bridge beams; of two drums one at each end of, and carried by, the supporting structure, two motors, one for each drum, driving connections between each motor and its corresponding drum; a trolley spanning and movable along the bridge beams, two sets of sheaves carried by the trolley, a sheave block, a hoisting hook thereon and sheaves carried by the sheave block, and ropes each having their opposite end portions wound upon the two drums and extending between the drums, one rope extending around one set of sheaves and a sheave or sheaves on the sheave block and the other rope extending around the other set of sheaves and a sheave or sheaves on the sheave block.

2. In a crane, the combination with a supporting structure comprising end trucks and connecting bridge beams; of two drums one at each end of, and carried by, the supporting structure, two motors, one for each drum, driving connections between each motor and its corresponding drum; a trolley spanning and movable along the bridge beams, two sets of sheaves carried by the trolley, a sheave block, a hoisting hook thereon and sheaves carried by the sheave block, ropes each having their opposite end portions wound upon the two drums and extending between the drums, one rope extending around one set of sheaves and a sheave or sheaves on the sheave block and the other rope extending around the other set of sheaves and a sheave or sheaves on the sheave

block, and means to brake the trolley sheaves; whereby, with the trolley sheaves unbraked, the load may be lifted at high speed without moving the trolley by winding the ropes on both drums or at low speed by winding the rope on only one drum, and whereby by braking the trolley sheaves and winding the rope on only one or the other drum the trolley may be moved in one direction or the other without vertical movement of the load.

3. In a crane, the combination with a supporting structure comprising end trucks and connecting bridge beams, of a trolley adapted to travel along the bridge beams, two sets of sheaves carried by the trolley, a hoisting-hook carrier and sheaves thereon, drums at each end of and supported on the supporting structure, ropes engaging and extending between the drums, intermediate parts of which engage the two sets of sheaves respectively and sheaves on the hoisting hook carrier, and means to operate either drum independently or both drums simultaneously to thereby turn the trolley sheaves at different speeds and thereby control the load lifting speed.

4. In a crane, the combination with a supporting structure comprising end trucks and connecting bridge beams, of a trolley adapted to travel along the bridge beams, two sets of sheaves carried by the trolley, a hoisting-hook carrier and sheaves thereon, drums at each end of and supported on the supporting structure, ropes engaging and extending between the drums, intermediate parts of which engage the two sets of sheaves respectively and sheaves on the hoisting hook carrier, stationary motors, one for each drum, supported on the supporting structure, and driving connections from each motor to its corresponding drum.

5. In a crane, the combination with a supporting structure comprising end trucks and connecting bridge beams, of a trolley adapted to travel along the bridge beams, two sets of sheaves carried by the trolley, a hoisting-hook carrier and sheaves thereon, drums at each end of and supported on the supporting structure, ropes engaging and extending between the drums, intermediate parts of which engage the two sets of sheaves respectively and sheaves on the hoisting hook carrier, means to brake the trolley sheaves, and power means to operate the drums whereby when the brakes are applied to the trolley sheaves the trolley may be moved along the bridge beams and whereby by unbraking the trolley sheaves the hoisting hook may be lifted without movement of the trolley.

6. In a crane, the combination with a supporting structure comprising end trucks and connecting bridge beams, of a trolley adapted to travel along the bridge beams, two sets of sheaves carried by the trolley, a hoisting-hook carrier and sheaves thereon, drums at each end of and supported on the supporting structure, ropes engaging and extending between the drums, intermediate parts of which engage the two sets of sheaves respectively and sheaves on the hoisting hook carrier, two stationary motors one at each end of the supporting structure, driving connections between each motor and the corresponding drum, and means to independently brake each set of trolley sheaves.

7. In a crane, the combination with a supporting structure comprising end trucks and connecting bridge beams, of a trolley adapted to travel along the bridge beams, two sets of sheaves carried by the trolley, a hoisting-hook carrier and

sheaves thereon, drums at each end of and supported on the supporting structure, ropes engaging and extending between the drums, intermediate parts of which engage the two sets of sheaves respectively and sheaves on the hoisting hook carrier, means to brake the two sets of trolley sheaves independently, and power means to operate the drums independently; whereby, with the trolley sheaves unbraked, the load may

be lifted at high speed without moving the trolley by winding the ropes on both drums or at low speed by winding the rope on only one drum, and whereby by winding the rope on only one drum the trolley may be moved in one direction and the load simultaneously lifted or not dependent on whether the trolley sheaves of only one set or the trolley sheaves of both sets are braked.
